UNITED STATES PATENT OFFICE.

DANIEL M. WYGOLD, OF DENVER, COLORADO.

DESIGN FOR A HUMIDOR.

55,446.

Specification for Design.

Patented June 8, 1920.

Application filed September 11, 1919. Serial No. 323,227. Term of patent 3½ years.

To all whom it may concern:

Be it known that I, DANIEL M. WYGOLD, a citizen of the United States, residing at Denver, in the county of Denver and State of Colorado, have invented a new, original, and ornamental Design for a Humidor, of which the following is a specification, reference being had to the accompanying drawing, forming a part thereof.

Figure 1 is a plan view of a humidor, showing my new design. Fig. 2 is a side view of the same. Fig. 3 is a view showing

that side of the humidor opposite to the side shown in Fig. 1. Fig. 4 shows an end view of the humidor.

I claim:

The ornamental design for a humidor, as shown.

In testimony whereof I have affixed my signature in presence of two witnesses.

DANIEL M. WYGOLD.
